RAILWAY TRAFFIC CONTROLLING
APPARATUS

Earl M. Allen, Swissvale, Pa., assignor to The
Union Switch & Signal Company, Swissvale,
Pa., a corporation of Pennsylvania

Application May 12, 1934, Serial No. 725,313

21 Claims. (Cl. 246—41)

My invention relates to railway traffic controlling apparatus, and particularly to apparatus of the type involving a railway switch which is controlled jointly by an operator located at a remote point and by traffic conditions in the vicinity of the switch.

More particularly, my present invention relates to apparatus of this character involving approach locking means which in normal operation becomes effective to lock the switch while a train is approaching, but is released when the train enters the track section in which the switch is located.

One feature of my invention is the provision, in apparatus of this character, of novel and improved means for preventing improper release of the approach locking means in the event of momentary failure of the source of track circuit current for the section of track in which the switch is located while such section is unoccupied.

I will describe one form of apparatus embodying my invention, and will then point out the novel features thereof in claims.

In the accompanying drawing, Fig. 1 is a diagrammatic view showing a portion of one form of apparatus embodying my invention. Fig. 2 is a diagrammatic view showing certain circuits for the control of relay M in Fig. 1.

Similar reference characters refer to similar parts in each of the views.

Referring first to Fig. 1, the reference characters 1 and 1^a designate the track rails of a stretch of main track E, which rails are divided by insulated joints 2 to form a main section X—Y and an approach section W—X. The main section X—Y contains a switch A leading into a side track C. Traffic moving toward the right through the main section X—Y is governed by two signals SA and SB, which signals are controlled in part by traffic conditions in the main section X—Y and will usually also be controlled from a remote point, such as an interlocking tower or a dispatcher's office. The control of these signals forms no part of my present invention, and, consequently, the controlling circuits are omitted from the drawing. The switch A is provided with an operating mechanism D, which is also controlled in part from a remote point, usually the same point from which the signals are controlled, through the medium of circuits which are represented in the drawing by the reference character G. Associated with the switch A is the usual approach locking relay M, having a front contact 8 included in the operating circuits for the switch mechanism D, so that the switch cannot be moved

through the medium of its operating circuits G unless this relay is energized.

The main section X—Y is provided with a track circuit comprising a source of current, such as a battery 3 connected across the rails at one end of the section, and a primary track relay P which is at times connected across the rails at the other end of the section. This section is provided with a second track circuit including a source of current, such as a battery 7 and a slow releasing secondary track relay S, which elements are at times connected in series across the rails of the section. The primary relay P is provided with a pick-up circuit which passes from the upper rail 1, through the winding of relay P, and a front contact 6 of the secondary relay S to the lower rail 1^a. It follows that this circuit is closed only when contact 6 on relay S is closed. Relay P is also provided with a holding circuit, which passes from the upper rail 1, through the winding of relay P, a front contact 4 of relay P, and a resistance 15 to the lower rail 1^a. It follows that this holding circuit is closed only when relay P is closed. When relay P is released, battery 7 and the winding of relay S are connected across the rails of section X—Y, through back contact 5 of relay P, but when relay P is closed this path is, of course, open at contact 5. When this path is closed, relay S will be energized when and only when the path is completed by the wheels and axles of a train in section X—Y.

The approach section W—X is provided with a track circuit of the usual type including a source of current 3 and a track relay T.

Referring now to Fig. 2, the approach locking relay M is provided with an energizing circuit which passes from terminal B of a suitable source of current, through a contact SA9 which is closed only when signal SA indicates stop, a contact SB10 which is closed only when signal SB indicates stop, front contact T11 of the approach track relay T, and the winding of relay M to terminal O of the same source of current. This circuit is provided with a shunt around contact T11, which includes a back contact P12 of the primary relay P, and a front contact S13 of the secondary relay S. The circuit for relay M is provided with a second shunt around contact T11, which second shunt includes a normally open contact of a manually operable time element device Q. The circuit for relay M is provided with a third shunt around contact T11, which third shunt includes front contact 14 of relay M.

When switch A is in the normal position, signals SA and SB are both at stop, and no trains

are in the vicinity of the switch, the parts of the apparatus are in the positions in which they are shown in the drawing.

I will now assume that the operator at the remote point takes suitable action to cause signal SA to give a proceed indication. This will open contact SA9, so that relay M will become deenergized, and this will prevent the operator from operating switch A. If, when there is no train in the approach section W—X, the operator returns signal SA to the stop position, relay M will again become energized so that the operator will be free to operate switch A. If, however, the section W—X is occupied by a train, the return of the signal SA to its stop position will not cause relay M to become energized because the main circuit for this relay will then be open at contact T11 of track relay T. Under these conditions relay M can be energized only by operation of the slow-acting device Q.

I will now assume that signal SA has been cleared and that a train moving toward the right passes through the stretch of main track shown in Fig. 1. When the train enters section X—Y, it will de-energize the primary relay P, thereby closing at back contact 5 the path by which battery 1 and secondary relay S are connected across the rails. Relay S will then become energized, because its circuit will be completed through the wheels and axles of the train. Signal SA will be returned to the stop position by virtue of the usual control of this signal by relay P. A pick-up circuit for relay M will then be closed through contacts SA9 and SB10, back contact P12 of relay P, and front contact S13 of relay S, so that relay M will again become energized. When the train leaves section X—Y, relay S will become de-energized because the train shunt is removed from the rails of this section, but due to the slow-releasing characteristic of this relay its contact 6 will remain closed long enough for relay P to become energized by battery 3 located at Y end of track section X—Y. Relay M will remain energized, so that the operator may now reverse the switch A if he cares to do so.

The operation of the apparatus when switch A is reversed and signal SB is clear will be apparent from the foregoing without detailed explanation.

One important feature of my invention lies in the fact that a momentary interruption of the supply of track circuit current for the main section X—Y, while this section is unoccupied and section W—X is occupied, cannot result in improper energization of relay M, because under these conditions relay S would remain de-energized due to the fact that there is no train in section X—Y to complete its circuit.

Another important feature of my invention lies in the fact that a momentary interruption of the supply of track circuit current for the main section X—Y which might be caused by any number of reasons, such for instance as malicious intent or a broken rail, will cause relay P to open; then a removal of the interrupting cause, such as the broken ends of a rail again making mechanical contact, cannot again energize relay P until the cause of interruption has been ascertained and relay P has been energized by a mechanical contact across rails 1 and 1^a or local energization.

Although I have herein shown and described only one form of apparatus embodying my invention, it is understood that various changes and modifications may be made therein within the

scope of the appended claims without departing from the spirit and scope of my invention.

Having thus described my invention, what I claim is:

1. In combination, a section of railway track containing a switch, a source of track circuit current connected across the rails of said section, a primary track relay and a secondary track relay, a pick-up circuit for said primary relay connected across the rails of said section and including a front contact of said secondary relay, a holding circuit for said primary relay connected across the rails of said section and including a front contact of the primary relay, means for connecting said secondary relay across the rails of said section through a back contact of said primary relay and an auxiliary source of current, and means for controlling said switch by said relays. 5

2. In combination, a section of railway track containing a switch, a source of track circuit current connected across the rails of said section, a primary track relay and a secondary track relay, a pick-up circuit for said primary relay connected across the rails of said section and including a front contact of said secondary relay, a holding circuit for said primary relay connected across the rails of said section and including a front contact of the primary relay, means for connecting said secondary relay across the rails of said section through a back contact of said primary relay and an auxiliary source of current, 10 and a locking relay for controlling said switch, 20 and a pick-up circuit for said locking relay including in series a back contact of said primary relay and a front contact of said secondary relay. 25

3. In combination, a section of railway track containing a switch, a track circuit for said section including a source of current connected across the rails and a primary track relay normally connected across the rails through its own front contact, a secondary relay connected across the rails of said section through an auxiliary source of current and a back contact of said primary relay, a pick-up circuit for said primary relay connected across the rails of said section 40 and including a front contact of said secondary relay, and means for controlling said switch by said relays. 45

4. In combination, a section of railway track containing a switch, a track circuit for said section including a source of current connected across the rails and a primary track relay normally connected across the rails through its own front contact, a secondary relay connected across the rails of said section through an auxiliary source of current and a back contact of said primary relay, a pick-up circuit for said primary relay connected across the rails of said section 50 and including a front contact of said secondary relay, a locking relay for controlling said switch, 60 and a pick-up circuit for said locking relay including in series a back contact of said primary relay and a front contact of said secondary relay. 65

5. In combination, a section of railway track containing a switch, a track circuit for said section including a source of current and a primary track relay each connected across the rails, a secondary track relay and an auxiliary source of current connected in series across the rails of said section, and means for controlling said switch 70 by said relays. 75

6. In combination, a section of railway track containing a switch, a track circuit for said section including a source of current and a primary track relay each connected across the rails, a 80 auxiliary source of current, and means for controlling said switch by said relays. 85

- secondary track relay and an auxiliary source of current connected in series across the rails of said section, a locking relay for controlling said switch, and a pick-up circuit for said locking relay including in series a back contact of said primary relay and a front contact of said secondary relay.
7. In combination, a section of railway track containing a switch, a source of track circuit current connected across the rails of said section, a primary track relay and a secondary track relay, means for normally connecting said primary relay across the rails of said section through its own front contact, auxiliary means for connecting said primary relay across the rails of said section when and only when said secondary relay is closed, means for connecting said secondary relay and an auxiliary source of current in series across the rails of said section when and only when said primary relay is open, and a controlling circuit for said switch including in series a back contact of said primary relay and a front contact of said secondary relay.
8. In combination, a section of railway track containing a switch, a track circuit for said section including a source of current and a primary track relay each connected across the rails, a secondary track relay and an auxiliary source of current connected in series across the rails of said section, and a controlling circuit for said switch including in series a back contact of said primary relay and a front contact of said secondary relay.
9. In combination, a section of railway track containing a switch, a track circuit for said section including a normally energized relay which releases when a train enters the section, a second track circuit for said section including a normally deenergized relay which becomes energized when a train enters the section and remains energized as long as the train remains in the section, and a controlling circuit for said switch including in series a back contact of said first relay and a front contact of said second relay.
10. In combination, a section of railway track containing a switch, a track circuit for said section including a normally energized relay which releases when a train enters the section, a second track circuit for said section including a normally deenergized relay which becomes energized when a train enters the section and remains energized as long as the train remains in the section, and means for controlling said switch jointly by said two relays.
11. In combination, a section of railway track, a track circuit for said section including a normally energized relay which releases when a train enters the section, a second track circuit for said section including a normally deenergized relay which becomes energized when a train enters the section and remains energized as long as the train remains in the section, and a traffic governing device associated with said section and controlled jointly by said two relays.
12. In combination, a section of railway track, a track circuit for said section including a normally energized relay which releases when a train enters the section, a second track circuit for said section including a normally deenergized relay which becomes energized when a train enters the section and remains energized as long as the train remains in the section, a traffic governing device associated with said section, and a controlling circuit for said device including in series a back contact of said first relay and a front contact of said second relay.
13. In combination, a section of railway track containing a switch, a contact arranged to be closed by a train occupying said section, a relay and a source of current, means effective when said contact is closed for connecting said relay and said source in series across the rails of said section, locking means for at times preventing operation of said switch, and means including a front contact of said relay for releasing said locking means.
14. In combination with a section of railway track and a source of current connected across the rails of said section, a track relay and an auxiliary relay, a pickup circuit for said track relay connected across the rails of the section and including a front contact of the auxiliary relay, a holding circuit for said track relay connected across the rails of the section and including a resistor adapted to be short circuited by said front contact, and a circuit effective to energize said auxiliary relay including a back contact of the track relay.
15. In combination with a section of railway track and a source of current connected across the rails of the section, a track relay and an auxiliary relay, a pickup circuit for said track relay connected across the rails of the section and including a front contact of the auxiliary relay, a holding circuit for said track relay connected across the rails of the section and including a resistor adapted to be short circuited by said front contact, and means for energizing said auxiliary relay when and only when the armature of the track relay is down.
16. In combination with a section of railway track and a source of current connected across the rails of the section, a track relay, a holding circuit for said relay connected across the rails of the section and including a resistor in series with the operating winding of the relay, a circuit controlling contact shunting around said resistor and normally open, a pickup circuit for said track relay connected across the rails of the section and including said contact, electromagnetic means effective when energized to close said contact, and means to energize the electromagnetic means rendered active in response to a train entering the section.
17. In combination with a section of railway track and a source of current connected across the rails of said section, a track relay and an auxiliary relay, a pickup circuit for said track relay connected across the rails of the section and including a front contact of the auxiliary relay, a holding circuit for said track relay connected across the rails of the section and including a resistor connected so as to be shunted by said front contact, another source of current, and a circuit effective to energize said auxiliary relay including said other source of current and a back contact of the track relay.
18. In combination with a section of railway track and a source of current connected across the rails of said section, a track relay and an auxiliary relay, a pickup circuit for said track relay connected across the rails of the section and including a front contact of the auxiliary relay, a holding circuit for said track relay connected across the rails of the section and including a resistor and a front contact of the track relay, and an energizing circuit for the auxiliary relay connected across the rails of the section and including a back contact of the track relay.

19. In combination with a section of railway track and a source of current connected across the rails of said section, a track relay and an auxiliary relay, a pickup circuit for said track relay connected across the rails of the section and including a front contact of the auxiliary relay, a holding circuit for said track relay connected across the rails of the section and including a resistor adapted to be short circuited by said front contact, another source of current, and an energizing circuit for said auxiliary relay connected across the rails of the section and including a back contact of the track relay as well as said other source of current, whereby said energizing circuit will become effective when and only when said section is occupied by a train.
20. In combination with a section of railway track and a source of current connected across the rails of said section, a track relay and an auxiliary relay, a pickup circuit for said track relay connected across the rails of the section

and including a front contact of the auxiliary relay, a holding circuit for said track relay connected across the rails of the section and including a resistor adapted to be short circuited by said front contact, another source of current, and a circuit for energizing said auxiliary relay from said other source of current when and only when said section is occupied by a train.

21. In combination, a section of railway track, a track circuit for said section including a first source of current and a normally energized relay which releases when a train enters the section, a second track circuit for said section including a second source of current and a normally de-energized relay which becomes energized when a train enters said section and remains energized as long as the train remains in the section, and a traffic governing device associated with said section and controlled jointly by said two relays.

20
EARL M. ALLEN.
